RESILIENT LINER AND CAP FOR CLOSING CONTAINERS

Henry J. Dorn, Western Springs, Ill., assignor to Continental Can Company, Inc., New York, N.Y., a corporation of New York

Filed July 23, 1962, Ser. No. 211,510

5 Claims. (Cl. 215—40)

This invention relates to resilient liners employed for seals over the mouths of bottles and like containers, and to the forming of the same.

It is known, in the Schneider United States Letters Patent 2,752,059, to place a mass of plastisol in a cap member and shape the mass under heat and pressure to form a liner which has a thin central portion extending over the container mouth and an annular portion of greater averaged thickness and formed by concentric projecting ribs alternating with grooves. These ribs are shown as of essentially the same height from the inner surface of the cap member. During application to the container, the ribs encounter the lip or curvature roll around the bottle mouth: as pressure is exerted in the axial direction of the container, the ribs are deformed elastically and conform to the lip so that, when a crown cap is crimped to the container ring, a maintained sealing effect results for resisting movements of and in the cap due to internal pressure in the container, for example.

It has been found that a superior type of sealing can be attained by having a first rib of greater height for first engaging the container lip, to be resiliently compressed thereagainst, and at least one other and lower rib located farther from the container axis and also resiliently compressed against the container lip during sealing. Therewith, during the closing and sealing, a compressed elastic annular mass fills the space between the container lip and the cap, with the portion of the annulus nearer the container contents under a greater elastic force than a portion farther from such contents.

An illustrative embodiment of the invention is shown on the accompanying drawings, in which:

FIGURE 1 is a diametrical section through a punch for forming a crown liner of the instant invention;

FIGURE 2 is a diametrical section of a crown closure shell on a platen and containing a mass of moldable liner material;

FIGURE 3 is a diametrical section of a crown closure shell with a molded liner therein, and with the outline of a standard bottle section shown in dotted lines;

FIGURE 4 is a diametrical section showing the crown closure in sealing position on a bottle;

FIGURE 5 is a section corresponding to a part of FIGURE 1, and on a greatly enlarged scale;

FIGURE 6 is a corresponding enlarged section corresponding to a part of FIGURE 3.

It is customary to mold liners in crown shells with the shell cavity open upwardly, and such is the position of parts in FIGS. 1 to 3. The closed and sealed bottles are usually stored with their mouths upward, and such is the position in FIG. 4. The several figures show sections; and it will be understood that the standard circular shapes about the bottle and shell axis A are present, and that the ribs are concentric circles.

The punch P shown in diametrical section in FIGS. 1 and 5 illustratively has a plane bottom surface 10 bounded by a circular edge 11 which can be 0.757 inch in diameter for the standard crown closure. This surface 10 will be employed in this description as a reference plane as to angularity and distance of other parts. A conical surface 12 extends upward and outward from the edge 11 at an angle of about 80 degrees; and provides with the outward

2

and downward conical surface 13 a groove 14 in which a rib can be molded in the liner. This groove illustratively has a depth from the reference plane of surface 10 of 0.031 inch, with the surface 13 at an angle of 45 degrees to the reference plane. The bottom or root 15 of the groove 14 may have a radius not greater than 0.005 inch provided that the aforesaid depth of 0.031 inch is present in the illustrative practice.

The surface 13 joins a second upwardly and outwardly conical surface 17 at a ridge 16 which is 0.005 inch above the reference plane, with the surface 17 at an angle of 45 degrees to such plane. The surface 17 joins a second outwardly and downwardly conical surface 18 at a groove root 19 to provide a second groove 20 with the groove root 19 at 0.017 inch above the reference plane. The surface 18 is at 45 degrees to the reference plane, and joins a third upwardly and outwardly conical surface 21 at a ridge 22 which is 0.005 inch above the reference plane. The surface 21 joins a third downwardly and outwardly conical surface 23 at a groove root 24 to provide a third groove 25. The surface 23 at a corner 26 joins a plane annular surface 27 which is parallel to and 0.008 inch above the reference plane and illustratively is 0.011 inch wide in the radial direction of the punch. The outer edge 28 of the surface 27 is formed at a fourth upwardly and outwardly conical surface 29 at 45 degrees to the reference plane and ending at a second plane annular surface 30 which can be 0.006 inch wide in the radial direction of the punch, and located parallel to and 0.031 inch above the reference plane 10. The outer edge 31 of the surface 30 is formed by an outer cylindrical surface 32 of the punch, which is joined by the curved surface 33 to the cylindrical surface 34 with the maximum diameter of 1.0525 inches for the punch, at the edge 35. The surface 32 can have a diameter of 1.029 inches, being smaller than the larger diameter TC and greater than the smaller diameter BC of the crown shell referred to the general axis A of the shell, liner and bottle, for the smooth portion of the shell below (FIGS. 2 and 3) the corrugated portion of the shell skirt and at top corner radius portion TCR.

The crown shell CS of FIG. 2 is illustratively of metal, and has an upwardly concave central domed portion CD which originally can have a radius of 6 to 8 inches. This portion CD merges smoothly into the top corner radius portion TCR; above which, in FIG. 2, are shown the corrugated edge structures CE.

In forming the crown liner in such a crown shell, a measured quantity of a thermo-plastic material is deposited as a mass PM on the central portion CD of the shell, while the shell is illustratively positioned on a platen BP. The punch P and the platen are heated: such is known, and the specific heating means is not shown.

The mass PM may be of a plastisol, for example of fine particles of vinyl chloride polymer resin in a plasticizer therefor such as diethyl phthalate. At room temperature, and up to about 130 degrees F., such a plastisol behaves as a viscous liquid, essentially without inter-diffusion of the resin and plasticizer. At higher temperature, e.g. 275 to 375 degrees F., inter-solution begins, and the plasticizer component becomes more viscous but still capable of flow under pressure at such temperature, by the dissolution of the polyvinyl resin therein; and the hard particles of polyvinyl resin become softer by the penetration of the plasticizer into them. When an appropriate time of heating at the selected temperature has occurred, the inter-diffusion produces essential uniformity homogeneity in the mass. For commercially available plastisols, this may be 3 to 15 seconds at 300 degrees F., or 1 to 5 seconds at 350 degrees F.; and such complete dissolution of one component into the other

is commonly called curing. At this cured stage, the completely inter-dissolved and cured mass is elastic, and returns resiliently when deformed by pressure. Such commercial plastisols have the polyvinyl resin particles and the plasticizer as components; and also often include inert filler particles, waxes and the like to prevent blocking and facilitate the flow during molding, and coloring matter. A property of such plastisols is that of liquidity as delivered and employed for forming the sticky masses PM. Upon heating, the mass becomes more viscous and form-maintaining, and adheres to the inner surface of the crown shell: such shells may have a baked coating of vinyl lacquer. The heating may occur in a single stage or in several stages. For example, the mass PM may be deposited, and then the shell region CD heated while the hot punch P is lowered into the shell, to engage and cause the liquid mass to spread radially as indicated by the arrows in FIG. 2. Shortly thereafter, the edge 31 of the punch comes into contact with the shell wall, below its corrugations; and acts mechanically to force the periphery of the crown shell downward, while the center of the dome portion CD is detained by the platen, so that the radius of the dome is increased. Therewith the radially spreading mass is confined by the engagement of the punch edge 31 with the shell, so that flowing material is restricted against flow beyond the edge 31, and instead is caused to become distributed between the punch and the shell. As the punch moves downward, the volume of the space between the punch and shell decreases; and also the flattening of the dome at portion CD acts to decrease the volume. Ultimately, the volume available is reduced to that required for the quantity originally deposited as the mass PM; at which state the mass has been distributed to fill the volume. Further downward movement is then restricted, so the mass acts as an essentially incompressible material: and in practice the punch or platen is spring-mounted so that further pressure does not produce change of their relative positions. The hot punch and shell are held in contact with the mass, after its shaping, until the curing is complete.

In another practice, the shell with the mass therein, as in FIG. 3, is heated until partial inter-dissolution has occurred; and then the punch is brought down, with heat and pressure, so the partially cured, adherent, and normally form-maintaining mass is caused to flow and fill the space between the punch and the shell.

These practices may be modified, and the punch time shortened, by withdrawing the punch after the mass has been shaped and has been rendered non-tacky and form-maintaining in its shaped condition; and then the shell with the shaped liner therein is further heated, as in a hot air oven, to complete the curing.

A further practice is to heat the assembly of FIG. 2 until the mass PM is completely cured; and then engage the punch P under heat and pressure for thermosoftening the elastomer and effecting the shaping of the liner.

In each practice when the mass PM is in position, the edge 31, FIG. 5, preferably comes into contact with the inner surface of the metal shell before parts of this mass, displaced outwardly by the punch pressure, come to the edge 31, noting that the grooves 14, 20, 25 successively receive the material. Concurrently with or shortly after the edge 31 engages the metal shell, the punch also engages the shell at the edge 35, and a second dam is formed. In the event the mass PM is not concentric with the axis A, and a part is flashed past the edge 31 before the dam forms thereat, the edge 35 scrapes along the smooth surface of the shell, below the skirt corrugations, so this partial flash is gathered and returned downward, being collected at 32a, noting FIG. 5, in the space between the punch surfaces 32, 33 and the metal shell.

The relationship of the ribs or rings to the top of the lip BL of the standard bottle is shown in FIG. 3; and

the corresponding shape after compression and crimping in FIG. 4.

In practice with crown closures having liners with concentric ribs with their crests or ridges at a common plane or in a common conical surface, the sealing performance is excellent with new, undamaged bottles. With trade-returned bottles, for beverages under pressure, troubles have occurred when the bottle lip has been chipped. The difficulties were particularly noted with beer bottles; the gas escapes and the pressure was lost, even without visual indication of liquid leakage. On study, much of the trouble occurred with bottles chipped around the outside of the locking ring. Increase of the amount of resilient material adjacent the top corner radius, so the region between the outside of the bottle lip and the inside of the metal skirt is filled with sealing compound under pressure as the bottle leaves the crimping operation, did not solve the troubles. By deepening the grooves and ridges and the base thickness from the roots of the grooves and the metal shell, to augment the axial distance of resilient action of the liner, the number of defectively sealed chipped bottles was reduced; but other troubles were then noted. Crowns with this deeper ring design were more susceptible to side-hit abuse: that is, a blow against the side wall or crown skirt could cause pressure loss. Further, when the filled and capped bottles were dropped through easier grids for alignment of a group of bottles in a case, the edge of the crown was more apt to catch on the grid or other projection, with disturbance to the seal.

It has been found that the difficulties can be overcome, by reducing the base thickness between the groove roots and the metal shell, by having an inside rib higher than outer ribs and positioned to engage the top of the bottle lip, by reducing the amount of material at the peripheral edge of the liner, and by providing two lines of engagement of the periphery of the molding punch with the inner surface of the closure shell. The changes in the heights of the sealing rings or ribs and the greater depths of the grooves between the rings give a greater, e.g. twice as much, downward movement of the closure shell under the axial pressure during bottle closing, as the resilient material is more free to move. The reduction of the amount of material at the edge of the liner assures that the clinching or crimping of the skirt corrugations radially inward and beneath the locking ring of the bottle occurs with an axial component of force against the reaction of the compressed sealing rings and thus to the top of the bottle lip; without being reduced by compression of material between the outside of the lip and the top corner radius of the cap, and the establishment of a fulcrum line at that region. The presence of the double engagement of the punch with the shell, during the shaping of the liner, provides a peripheral pocket space between the two lines of engagement or dams, in which any flash forces beyond the inner line is distributed peripherally, instead of moving axially along the skirt and into the skirt corrugation areas where it is present between the skirt and locking ring and can prevent a tight metal-to-glass crimping upon a bottle.

Of the several changes, the employment of a deep rib 14a on the liner, for engagement with the top of the container lip (FIG. 4) so that it bends and deforms under the capping pressure, and with a radially outward groove and rib for completing the sealing annulus, has been found most important. During the distortion under capping pressure, the shallower rib acts to provide a resilient resistance to outward expansion of the deeper rib: and together they establish an essentially solid but elastic sealing mass between the top of the bottle lip and the inside of the cap.

The liner adheres to the inner surface of the metal shell, and can have the form shown in FIG. 6, it being understood that the flattening of the dome portion CD of the shell is not necessarily followed by return to the

original radius of curvature when the punch is retracted upwardly but this portion can be flatter. In the illustrative embodiment, a standard crown shell CS is indicated, with the central dome portion CD having a cross-sectional curvature of FIG. 2 with radii of 6 to 8 inches when the plastisol is inserted, and being modified by the action of the molding punch so the radii are 10 to 11 inches in FIGS. 3 and 4.

The thickness of the central portion 40 of the liner, within the inside ring or rib, can be 0.005 inch. In FIG. 6, the parts of the liner are shown as produced by the mating parts of the forming punch of FIG. 5; thus the groove 14 of the punch provides the inner rib or ring 14a of the liner, the ridge 16 of the punch provides the groove root 16a of the liner, and so on. The roots 16a and 22a are about 0.009 inch from the inner surface of the metal shell, in the illustrated form; the surface 27a is at a lesser distance due to the curvature of the shell. The portion 29a along the top corner radius can be less than 0.005 inch; its presence being preferred to assure liner adhesion outside the region of the surface 27a. The region 32a indicates a minor local flash which has passed beyond the engagement 31a on the shell by the edge 31 on the punch: noting that this is below the second damming point 35a.

During capping, the ribs 14a, 20a and 25a are engaged with and compressed against the top of the bottle lip BL, as shown in FIG. 4. The material of these ribs spreads radially inward and outward under the compression forces. The crimping tool acts against the periphery of the corrugated region CE of the shell skirt, as indicated by the arrows in FIG. 4, to cause parts CC of the corrugations to engage beneath the locking ring LR of the bottle. It will be noted that the masses 29a, 32a of FIG. 6 are not active, in FIG. 4, to deflect or divert the crimping forces upon parts CC from cooperating with the axial forces of the seating ram, shown as arrow SR, in assuring maintenance of the seal at the annular compressed mass SM provided by the several ribs. In FIG. 4, the lines 50, 51, 52 respectively represent the prescribed standard or normal shape of the bottle lip, the permissible largest mouth size, and the permissible smallest mouth size. In each instance, it will be noted that all ribs act against the top of the lip.

It will be understood that the illustrative practice is not restrictive, and that the invention can be practiced in other ways within the scope of the appended claims.

What is claimed is:

1. A resilient liner and cap structure for closing a container, comprising a cap having a peripheral skirt and a central wall portion, and a liner of elastic material in said cap, said liner having at least two concentric ribs for engaging an upper surface of the lip of the container to be elastically compressed thereagainst, the radially inward rib being deeper than the radially outward rib whereby the inner rib is first engaged with the upper surface of the container lip and is flattened and compressed thereagainst before the outer rib encounters the container lip.

2. A resilient liner and cap structure for closing a container, comprising a cap having a skirt and a central wall portion and a top corner radius portion merging with the skirt and the central wall portion, and a liner of elastic material in said cap and extending over and adhering to the central wall portion thereof, said liner having a plurality of concentric ribs all located for engagement with a top of the lip of the container to be elastically compressed against and deformed thereby, the radially

inward rib being deeper and having a greater cross-section of the material and separated from the next outward rib by a groove whose root is spaced from the adjacent cap surface, all said ribs being located radially inward from the cap skirt so that upon compression against the top of the container lip they form an essentially solid mass of elastic material between the container lip and the adjacent parts of the top corner radius and central wall portion of the cap and with said mass spaced from the engagement of the cap with the container.

3. A sealed assembly of a container and a lined cap structure, the container having a lip surrounding its mouth and a locking ring, said cap structure including a central wall portion extending over the container mouth, a corrugated skirt in crimped engagement with the locking ring, and a top corner radius portion merging with the central wall portion and terminating short of the corrugations of the skirt, and a liner adherent in said cap, the invention which comprises the presence of an annular part of said liner as a compressed elastic mass between the container lip and the cap structure, the annular portion of said mass adjacent the container mouth exhibiting greater elastic forces than other parts of said mass, and the mass having annular regions exhibiting high elastic forces alternating with annular regions of less elastic forces, with the space between the container and the cap between the top corner radius portion and the skirt corrugations being free of compressed liner material.

4. A resilient liner and cap structure for closing a container of the type having an open mouth of predetermined diameter and a lip portion surrounding said open mouth, said lip portion having a predetermined inner and outer diameter and said inner diameter being equal to the predetermined diameter of said mouth; said liner having a plurality of concentric ribs located for engagement with the lip portion of the container, the radially inward rib being deeper and having a greater cross-section than the rib adjacent to and outwardly spaced therefrom, said radially inward rib having a diameter larger than the predetermined diameter of said mouth.

5. A resilient liner and cap structure for closing a container of the type having an open mouth of predetermined diameter and a lip portion surrounding said open mouth, said lip portion having a predetermined inner and outer diameter and said inner diameter being equal to the predetermined diameter of said mouth; said liner having a plurality of concentric ribs, the radially inward rib having a greater cross-section than the rib adjacent to and outwardly spaced therefrom, said radially inward rib having a diameter larger than the predetermined diameter of said mouth, said plurality of concentric ribs being located for engagement with the lip portion of the container between the inner and outer diameter of said lip portion, the rib adjacent to the inner diameter of the lip portion being deeper than the other of said ribs.
